UNITED STATES PATENT OFFICE.

FRED D. HOLDSWORTH, OF CLAREMONT, NEW HAMPSHIRE, ASSIGNOR TO SULLIVAN MACHINERY COMPANY, OF CLAREMONT, NEW HAMPSHIRE, A CORPORATION OF MAINE.

INTERCOOLER.

No. 898,363.

Specification of Letters Patent.

Patented Sept. 8, 1908.

Application filed September 9, 1907. Serial No. 391,926.

To all whom it may concern:

Be it known that I, FRED D. HOLDSWORTH, a citizen of the United States, residing at Claremont, in the county of Sullivan and State of New Hampshire, have invented an Improvement in Intercoolers, of which the following description, in connection with the accompanying drawings, is a specification, like letters on the drawings representing like parts.

This invention relates to intercoolers, more particularly intended for cooling the air in air compressors or the like.

In order that the principles of the invention may be clearly understood, I have shown a single type or embodiment thereof in the accompanying drawing, wherein

Figure 1 is a vertical central sectional view of an intercooler embodying my invention; Fig. 2 is a transverse section upon the line 2—2 of Fig. 1; Fig. 3 is a transverse section upon the line 3—3 of Fig. 1; Fig. 4 is a transverse section upon the line 4—4 of Fig. 1; and Fig. 5 is a detail in vertical section showing the preferred manner of securing the tubes and of supporting the baffle plates.

Referring to the single type or embodiment of the invention herein illustrated, the shell of the intercooler is represented at 1, it being of any suitable material, such as cast iron, and is bolted or otherwise secured to the base 1'. Such shell is preferably of a generally cylindrical form, one end thereof being provided with a preferably cast iron head 2, the top plate 3 whereof may be secured thereto as by bolts 4. The said head may be secured to the shell in any suitable manner as by bolts 5. The shell is provided with an inlet 6 for the medium that is to be cooled, which, in the present type of the invention, is air. A suitable outlet 7 is provided for the air, preferably at the opposite end of the shell. Herein said inlet and outlet are disposed upon opposite sides of the shell. Depending from the head 2 is a series of metallic pipes preferably of copper, the pipes being secured in the said head in any suitable manner and preferably by expanding the ends thereof, as indicated at 9 in Fig. 5, into intimate engagement with correspondingly shaped openings 10 in the cast iron head. Any suitable number of such pipes may be provided. As shown at 11 in Fig. 1, an inlet is provided in the head 2 for a cooling medium, which may be water. An exit for the water is indicated

at 12, it preferably being provided in the head 2 at a point oppositely disposed from the inlet 11. Preferably a transverse partition 13 is formed in the head 2 to compel the desired circulation of the water through the tubes 8. In order to provide for free expansion or contraction of the copper tubes 8, the lower ends thereof are not secured to a fixed portion of the casing or a fixed head, but are mounted in any suitable manner in a lower head 14, as by expanding the lower ends of said pipes thereinto in a manner similar to that indicated in Fig. 5. The said lower head is hollow and is provided with a draining pipe 15 passing through a stuffing box 16, the construction being such as to permit movement of the lower head 14 and the drain pipe 15 toward and from the head 2, due to the contraction and expansion of the copper tubes 8. The pipe 15 may, if desired, be provided with a suitable valve to control the drainage of water from the tubes 8.

The tubes 8 are of any suitable diameter and are disposed in a number of rows or series, as clearly indicated in Figs. 2, 3 and 4, the pipes of each row preferably being arranged staggering with reference to those of the adjacent rows as clearly indicated. Preferably also the pipes are arranged closely adjacent each other. The baffle plates 17 are provided, as indicated in Fig. 1, preferably extending alternately from opposite sides of the casing 1 to compel the air or other fluid that is to be cooled to partake of a circuitous course in passing from the inlet 6 to the outlet 7. While the baffle plates may be positioned and secured in any desired manner, herein I provide tie rods 18, clearly indicated in Fig. 1 and 5, extending from the head 2 to the lower baffle plates. In order to space and support the various plates, tubes 19 are provided of proper length and surrounding the tie rods, each baffle plate 17 being supported between adjacent tubes 19, as clearly indicated in Fig. 5.

By the described construction, the air is forced to take a sinuous course between the staggered tubes, thus breaking the air up into thin streams and causing every portion thereof to come into actual contact with the cold surfaces of the pipes. In order effectually to cool heated air, it is necessary to bring each portion thereof into actual contact with the cooling medium, as air parts very slowly with its heat by direct radiation.

The baffle plates increase the distance traversed by the air and cause it to strike against the tubes 8 squarely or approximately at right angles respectively throughout the 5 length of the tubes, so that the full effective force of the cold water or other cooling medium is received by the air.

Preferably the lower portion of the casing 1 is enlarged, as indicated at 20 in Fig. 1, so 10 that the velocity of the descending air is reduced, thus giving time for moisture that may be condensed from the air upon the tubes or the interior of the casing and hence discharged into the bottom of the casing, 15 from being swept out at the outlet by too rapid a current. Preferably the upper portion of the shell is made of as small a diameter as possible consistent with assembling in order to keep the air in intimate contact 20 with the tubes. The casing 1 is closed at the lower end by a plate 21, wherein is preferably mounted a drain pipe 22 whereby water condensing upon the exterior of the tubes or elsewhere may be drained from the casing. 25

In order to prevent the air as it enters the enlarged portion 20 of the casing from passing directly into the outlet 7, I have provided a deflecting plate 23 herein represented as semi-circular in form. Preferably the lower 30 enlarged portion of the casing is provided with a hand hole 24 having a covering plate 25. If desired, a safety valve 26 and a pressure gage 27 may be provided in conjunction with the intercooler. 35

Water or other cooling medium may be entered under pressure through the inlet pipe 11 and passes down through the tubes 8 arranged at the right hand side of the partition 13, viewing Fig. 1, thence rising through 40 the tubes 8 at the left hand side of the partition 13, viewing said figure, and is discharged through the outlet 12. It is apparent that the inlet and outlet passages 11 and 12 may be arranged at any desired point with relation to each other. 45

Having thus described one type or embodiment of my invention, I desire it to be understood that although specific terms are employed they are used in a generic and descriptive sense and not for purposes of limitation, the scope of the invention being set forth in the following claims. 50

Claims.

1. An intercooler for compressors or the like comprising a casing having inlet and outlet passages for the fluid to be cooled, a head mounted upon one end thereof, said head being chambered and provided with a partition, inlet and exit pipes for the cooling medium communicating with the chambered portion of said head upon opposite sides of said partition, a stack of tubes extending from said head longitudinally of said casing a second head to which the opposite ends of said tubes are secured, said second head be-

ing unconfined except by said stack of tubes, the portion of the casing wherein the second head is located being enlarged, and means to compel a circuitous circulation of the fluid to be cooled in said enlarged portion of the casing. 70

2. An intercooler for compressors or the like comprising a casing having inlet and outlet openings for the fluid to be cooled, a head mounted upon one end of said casing and provided with inlet and outlet passages for the cooling medium, tubes secured to said head and extending therefrom longitudinally of said casing, a head to which the opposite ends of said tubes are secured, said head being unconfined to permit expansion and contraction of said tubes and means guarding the outlet opening for the fluid to be cooled and compelling a circuitous circulation of said fluid about the last mentioned head. 80

3. An intercooler comprising a casing 1 having inlet and outlet passages 6 and 7 for the fluid to be cooled, a head 2 having inlet and outlet passages 11 and 12 for the cooling medium, a stack of pipes extending from said head, a head 14 to which the opposite ends of said pipes are secured, said head 14 being unconfined laterally and longitudinally, thereby to permit expansion and contraction of the tubes means guarding the outlet opening for the fluid to be cooled and compelling a circuitous circulation of the fluid, and a draining tube 15 for the head 14. 90

4. An intercooler for compressors or the like comprising a casing having inlet and outlet passages 6 and 7 for the fluid to be cooled, a head 2 at one end of said casing having an inlet passage 11 for the cooling medium, a stack of pipes extending from said head longitudinally of said casing, means extending transversely of said casing and intermediate the inlet and outlet openings to direct the medium to be cooled in a path at substantially right angles to the tubes and means guarding the outlet passage 7, thereby compelling the fluid to be cooled to partake of a circuitous path about the adjacent portion of the stack of tubes. 100

5. An intercooler comprising a casing provided with inlet and outlet openings 6 and 7, a head having an inlet opening 11, a stack of tubes extending from said head substantially longitudinally of said casing, baffle plates 17 to compel the fluid to be cooled to partake of a circuitous route in passing from the inlet to the outlet opening the exit end of the casing being provided with an enlarged chamber and a deflecting plate in such enlarged chamber guarding the outlet 7. 115

6. An intercooler for compressors or the like comprising a casing 1 having inlet and outlet openings 6 and 7 for the fluid to be cooled, the end of the casing adjacent the outlet opening being of enlarged diameter, a 120

- head 2 at one end of the casing having inlet and outlet pipes 11 and 12 for the cooling medium, a stack of tubes extending from the head 2 into the enlarged portion of the casing, a head 14 in said enlarged portion to which the opposite ends of said tubes are secured, and baffle plates 17 extending transversely of the casing 1 intermediate the inlet and outlet openings 6 and 7. 5
- 10 7. An intercooler for compressors or the like comprising a casing 1 having inlet and outlet openings 6 and 7 for the fluid to be cooled, a head 2 having a pipe 11 for the entrance of the cooling medium, a stack of tubes extending from said head 2, a head 14 to which the opposite ends of said pipes are secured, said head being otherwise unconfined, means to compel a circuitous circulation about said head tie rods 18 extending from said head 2, and baffle plates 17 supported by said tie rods. 15
- 15 8. An intercooler for compressors or the like comprising a casing 1 having a chambered head 2 provided with a partition 13, inlet and outlet pipes 11 and 12 upon opposite sides of said partition, a stack of tubes depending from the head 2, a head 14 to which the opposite ends of the pipes are secured, said head being unconfined to permit 20 expansion and contraction of said tubes, tie rods extending longitudinally of said casing, and baffle plates 17 supported by said tie rods. 25
- 30 9. An intercooler for compressors or the like comprising a casing 1 having inlet and outlet openings 6 and 7 for the fluid to be cooled, a head 2 mounted upon one end of the casing, said head being chambered and provided with a partition 13, inlet and outlet pipes 11 and 12 for the cooling medium, a stack of tubes depending from said head 2, a head to receive the opposite ends of said pipes, tie rods extending longitudinally of said casing, baffle plates 17 extending transversely of said casing, and tubes mounted upon said tie rods to support said baffle plates. 35
- 40 10. An intercooler for compressors or the like comprising a casing 1 having inlet and outlet passages 6 and 7, a chambered head 2 having an inlet pipe 11, a stack of tubes depending from said head, the lower portion of said casing being enlarged to permit reduction in velocity of the fluid to be cooled, and a partition 23 partially encircling the lower ends of said tubes at said enlarged portion of the casing. 45
- 45 11. An intercooler comprising a casing 1 having inlet and outlet passages 6 and 7 for the fluid to be cooled, a chambered head 2 having a partition 13 therein and inlet and outlet pipes 11 and 12 upon opposite sides of said partition, a stack of tubes depending from the lower portion of said chambered 50
- 55 head, said pipes being substantially equally distributed upon opposite sides of said partition, the casing 1 having an enlarged lower end, a chambered head to which the lower ends of the pipes are secured, a portion of the wall of the casing above the enlarged end being extended into the enlarged end to afford a partition 23 partially encircling the depending tubes adjacent the outlet opening, and baffle plates 17 intermediate the inlet and outlet openings. 55
- 60 12. An intercooler comprising a head provided with inlet and outlet openings at opposite end portions, a head having an inlet opening, a stack of tubes extending from said heads substantially longitudinally of the casing, baffle plates extending transversely of said tubes to compel the fluid to be cooled to partake of a circuitous route in passing from the inlet to the outlet opening, the casing being provided adjacent the outlet opening 65 with an enlarged chamber into which the tubes extend, said chamber being provided with a plate guarding the outlet opening and compelling a circuitous route of the fluid to be cooled. 70
- 70 13. An intercooler comprising a casing provided with inlet and outlet openings at opposite end portions, a head having an inlet opening, a stack of tubes extending from said head substantially longitudinally of the casing, baffle plates in said casing arranged transversely of the tubes, the casing being provided with an enlarged chamber adjacent the outlet, and a second head to which the opposite ends of said pipes are secured, said second head and a portion of the tubes leading thereto being arranged in said enlarged chamber whereby a circulation about said head and said portion of the tubes is permitted. 75
- 75 14. An intercooler comprising a casing provided with inlet and outlet openings at opposite end portions, a head having an inlet opening, a stack of tubes extending from said head substantially longitudinally of the casing, baffle plates in said casing arranged transversely of the tubes, the casing being provided with an enlarged chamber adjacent the outlet, a second head to which the opposite ends of said pipes are secured, said second head being arranged in said enlarged chamber, and a deflecting plate 23 in said enlarged chamber arranged in a position to compel the fluid to be cooled to partake of a circuitous route in said chamber about said tubes. 80
- 80 15. In testimony whereof, I have signed my name to this specification, in the presence of two subscribing witnesses.
